DIE FOR PUNCH PRESSES AND THE LIKE

Henry John, Sharon, Pa., assignor to Carnegie-Illinois Steel Corporation, a corporation of New Jersey

Application May 25, 1942, Serial No. 444,436

3 Claims.

(Cl. 153—51)

This invention relates to dies for punch presses and the like and, particularly to an improved apparatus or die for use in presses for straightening metallic material, such as armor plate and the like.

It is the general practice in the steel industry to straighten heavy steel plates, such as armor plates, after they have been heat treated. Such straightening is usually done by means of a heavy hydraulic or brake press which bends the plate beyond the elastic limit of the steel in a direction opposite that of the bend, kink or other irregularity in the plate. A pair of dies for contacting the opposite sides of the plate so as to bend the same is assembled in the press for such straightening operations.

Heretofore, one of the dies consisted generally of a slab or die block having a recess therein on the outer face thereof into which the plate being straightened was pressed, and the other or opposed die consisted of a slab or die block having a projecting portion or face which was adapted to cooperate with the recess in the opposed die to straighten any irregularities in the plate. Such bends or other irregularities may be located at various points along the plate and also may be in any direction with reference to the surface or edges of the plate. To remove the bends or other irregularities by dies heretofore mentioned and other dies heretofore suggested and used, it was necessary oftentimes to turn the plates over quite frequently in order that the male and female dies were disposed in the proper side of the bend or kink in the plate. Such turning of the plates was not only tedious but also consumed a considerable amount of time, thereby interfering with production. Therefore, it will be seen that such procedure was not entirely satisfactory.

Accordingly, it is one of the objects of the present invention to provide an improved apparatus or die for use with presses for straightening metallic plates which eliminates any need of turning the plate over to straighten the same regardless of the direction of the irregularity therein after the same has once been assembled between the dies, thereby eliminating excessive handling of the plates and reducing the plate-straightening time to a minimum.

It is another object of the invention to provide an improved die for use with presses for straightening metallic plates which can be used either as a female or a male die member, and one which can be easily and quickly converted from one to the other.

It is still a further object of this invention to provide an improved die for use with presses for straightening metallic plates which is simple and inexpensive in its construction, and at the same time, a die which is efficient and effective in its use.

Various other objects and advantages of this invention will become more apparent during the course of the following specification and will be particularly pointed out in the appended claims.

In the accompanying drawing there is shown, for the purpose of illustration, an embodiment which my invention may assume in practice.

In the drawing:

15 Fig. 1 is a vertical section through the improved die of my invention, showing the same assembled in position in a press for straightening plate material; and

20 Fig. 2 is a sectional view taken on line II—II of Fig. 1.

Referring more particularly to the drawing, the improved die of my invention comprises a rectangular-shaped body member or die block 2 having a base portion 3 and vertically extending side portions 4. There is arranged between the side portions 4 of the die block 2, a plurality of spaced apart reciprocably arranged block-like members 5, namely three in the present instance. The ends of the block-like members 5 are disposed in vertically arranged guide grooves 6 arranged on the inner sides of the side portions 4 for guiding the block-like members in their reciprocable movement. There is arranged in each of the guideways 6 centrally thereof, an inwardly projecting portion preferably in the form of a pin 7 which is adapted to extend into a slotted hole or opening 8 arranged in the respective end of the block-like member 5.

On top of the base portion 3 of the die block 2 and directly below the block-like members 5, there is disposed a longitudinally extending plate-like member 9 having a plurality of raised or cam portions 10 disposed on the upper side thereof which are adapted to cooperate with the inner or lower sides of the block-like members 5 in a manner hereinafter to be described. The plate-like member 9 is arranged for sliding movement relative to the base portion 3 and the block-like members 5, and the edges thereof are preferably disposed in horizontally or longitudinally extending guide grooves 12 arranged in the side portions 4 adjacent the bottom thereof directly above the bottom portion 3 of the body member. The bottom side of the plate-like member 9 is preferably recessed as at 13 so as to

provide suitable stop portions 14 at each end thereof. An upwardly extending portion 3a of the base portion 3 is adapted to fit in the recess 13 with the stop portions 14 carried by the plate-like member 9 adapted to cooperate with the ends thereof so as to limit the horizontal movement of the plate-like member and to position the same in the proper position after adjustment.

It will be understood that the inner or lower sides of the block-like members 5 rest upon and bear directly against the upper or outer side of the plate-like member 9. The cam-like portions 10 carried by the plate-like member 9 are adapted to cooperate with the inner or lower sides of the block-like members 5 so as to move the same from a retracted position between the side walls of the body member to a projected position thereabove so that a portion of the block-like members will extend above the side walls and the remaining portion of the body member when they are disposed in their projected position. It will be understood that the cam portions 10 are arranged on the plate 9 so that the outermost block-like members 5 are in their projected or raised positions when the cam portions disposed directly therebelow with the center block-like member adapted to assume a retracted position, as shown in Fig. 1 of the drawing. The purpose of the pins 17 is to limit the upward movement of the block-like members 5 and to retain these members in the die block at all times so as to prevent escapement of the same therefrom.

At each end of the plate-like member 9, there is arranged therethrough preferably a hole or opening 15 which is adapted to be in alignment when the plate is in one position with a similar hole 16 arranged in each end of the base portion 3 of the body member. There is provided preferably a tapered pin member 17 having a handle portion 18 carried thereby for insertion through the hole 15 in the plate 9 and the hole 16 in the base portion 3 so as to lock the plate in the desired position.

The improved die of my invention functions in the following manner:

It will be understood that the die of my invention is adapted to be used primarily for straightening metallic plates, such as steel armor plates and the like, and that it may be used with any conventional-type press. There is provided an upper and lower die which are identical and each is constructed in the manner hereinbefore described. One of the dies is positioned on the platen of the press with which the dies are to be used and the other or upper die is positioned directly opposite the lower die and attached to the ram of the press. The plate P to be straightened is placed between the dies in the press and if the plate to be straightened has an upward bend or kink therein, i. e. a bend extending upwardly from the top surface of the plate as it is positioned between the dies, as shown in Fig. 1 of the drawing, in order to remove such bend therefrom, it is necessary to bend the plate at the bend in a downwardly direction. To remove such a bend by means of the die of the present invention, the plate 9 of the bottom die, together with the cam portions 10 carried thereby, is moved to the left as shown in Fig. 1 of the drawing and the plate 9 of the upper die, together with the cam portions 10 carried thereby, is moved to the right. It will be understood that the block-like members 5 are moved to their projected positions and held in

such positions by the camming action of the cam portions 10 carried by the plate 9. The respective pins 17 are then inserted into the aligned holes 15 and 16 in the plates 9 and the base portion 3, respectively, so as to lock the plates in position. With the plates and cam portions arranged in such position, it will be seen that the two outer blocks of the bottom die and the center block of the top die are in their projected or raised positions while the remainder of the blocks, namely the outer blocks of the upper die and the center blocks of the lower die, are disposed in their lowered or retracted positions. It will also be seen that with the cam plates arranged in such position the block-like members 5 of one die will assume their retracted positions when the directly opposed block-like members of the other die assume their projected positions. The inner and outer side edges of each of the block-like members 5 are preferably relieved as at 19 with the relieved edges on the lower sides of the blocks 5 adapted to provide a better camming action between the cam portions 10 and the lower sides of the blocks 5 and with the relieved portions on the upper sides of the blocks adapted to provide a better surface for contacting the face of the plate to be straightened so as not to mark the same. With the block-like members 5 disposed in the positions as shown in Fig. 1, it will be seen that the plate P will be bent in a direction opposite that of the bend therein upon operation of the ram of the press; that is, the center block-like member 5 of the upper die which is in its projected position, is disposed opposite the center of the bend on the upper side thereof and the two outer block-like members 5 of the lower die are positioned to either side of the center of the kink. When the upper die is moved downwardly by the ram the projected center block 5 of the upper die will tend to bend the plate P about the projected outermost blocks 5 of the lower die which act as fulcrums.

If it is desired to remove a downwardly extending bend or kink from the plate P, i. e. a bend extending downwardly from the bottom surface of the plate as it is positioned between the dies, the position of the plate-like members 9, together with the cam portions 10 carried thereby, is reversed to that shown in Fig. 1 of the drawing; that is, plate 9 of the upper die is moved to the left and that of the lower die to the right. In such position it will be seen that the center block 5 of the lower die, together with the blocks of the upper die, is in its projected position and that the other blocks are in their retracted positions. With the blocks 5 in such position, it will be seen that when the ram of the press is operated so as to move the upper die downwardly and in engagement with the top surface of the plate, the plate P will be bent upwardly to remove the bend therefrom.

As a result of my invention, it will be seen that there is provided an improved die which can be used either as a female die member or a male die member, thereby providing a die which is extremely flexible in its use. By providing such a die for use in presses for straightening metallic plates it will be seen that the die can be easily and quickly converted from a male die to a female die or vice versa, thereby eliminating the necessity of turning the plate over from time to time for straightening of bends or kinks disposed in opposite directions. It will be seen that the die of the present invention is extremely simple in its operation and use and will effectively

remove any irregularities from a plate so as to straighten the same properly.

While I have shown and described a specific embodiment of my invention, it will be understood that this embodiment is merely for the purpose of illustration and description and that various other forms may be devised within the scope of my invention, as defined in the appended claims.

I claim:

1. Apparatus for straightening metallic plates and the like, including a pair of opposed dies, a plurality of spaced apart movable block-like members carried by each of said dies with each of said block-like members being positioned directly opposite a block-like member in the opposed die, said block-like members of each of said dies in one position adapted to project beyond the other block-like members and the remaining portions of the die and in another position adapted to assume a retracted position inwardly from the remaining portions thereof with the block-like members of one of said dies adapted to assume their retracted positions when the directly opposed block-like members of the opposed die assume their projected positions, at least one of said block-like members of each of said dies adapted to assume a retracted position when the other block-like members assume their projected positions, means carried by each of said dies for guiding the respective block-like members carried thereby in their movement to their retracted and projected positions, a plate-like member carried by each of said dies and arranged rearwardly of said block-like members, and a plurality of spaced apart cam portions carried by each of said plate-like members which are adapted to cooperate with said block-like members, said block-like members adapted to assume normally a retracted position and said plate-like member upon movement thereof adapted to move said block-like members by a camming action of the cam carried thereby to their projected positions.

2. Apparatus for straightening metallic plates and the like, including a pair of opposed identical dies, each of said dies comprising a body member, a plurality of spaced apart movable block-like members carried by said body member with each positioned directly opposite a corresponding block-like member of the opposed die, each of said block-like members being arranged for reciprocal movement in their respective body members and in one position adapted to assume a projected position extending outwardly from the body member and in another position adapted to assume a retracted position substantially within the body member, said block-like members being arranged so as to provide a space therebetween when disposed in their projected position at least one of the block-like members

carried by each of said body members adapted to assume a retracted position when the directly opposed block-like members carried by the opposed body member assumes a projected position whereby the projected block-like member of each of said dies contacts opposed faces of the plate adapted to be straightened and acts as a fulcrum during the movement of the dies toward each other, and means for moving and holding said block-like members in their projected positions relative to their respective body members, said last named means comprising a reciprocable cam member carried by each of said body members and arranged rearwardly of said block-like members with which it is adapted to cooperate, said block-like members adapted to assume normally a retracted position and said cam member adapted to move the block-like members by a camming action to their projected positions.

3. Apparatus for straightening metallic plates and the like, including a pair of opposed identical dies, each of said dies comprising a body member, a plurality of spaced apart movable block-like members carried by said body member with each positioned directly opposite a corresponding block-like member of the opposed die, each of said block-like members being arranged for reciprocal movement in their respective body members and in one position adapted to assume a projected position extending outwardly from the body member and in another position adapted to assume a retracted position substantially within the body member, said block-like members being arranged so as to provide a space therebetween when disposed in their projected position at least one of the block-like members carried by each of said body members adapted to assume a retracted position when the directly opposed block-like member carried by the opposed member assumes a projected position whereby the projected block-like member of each of said dies contacts opposed faces of the plate adapted to be straightened and acts as a fulcrum during the movement of the dies toward each other, and means for moving and holding said block-like members in their projected positions relative to their respective body members, said last named means comprising a movable plate-like member carried by each of said body members and arranged rearwardly of said block-like members carried thereby, and a plurality of cam portions carried by said plate-like member which are adapted to cooperate with said block-like members, said block-like members adapted to assume normally a retracted position and said plate-like member upon movement thereof adapted to move said block-like members to their projected positions by the camming action of the cam portions carried thereby.

HENRY JOHN.
